CLAIM

The ornamental design for a pallet stopper for a pallet support rack, as shown and described.

DESCRIPTION

FIG. 1 is a perspective view of a pallet stopper for a pallet support rack showing my new design;

FIG. 2 is a top view thereof;

FIG. 3 is a bottom view thereof;

FIG. 4 is a side view thereof, the opposite side view being a mirror image;

FIG. 5 is an end view thereof; and,

FIG. 6 is an opposite end view thereof.

The broken lines in FIG. 1 and showing attached structure is for illustrative purposes only and forms no part of the claimed design.
